CLAIM

The ornamental design for a spray bottle, as shown and described.

DESCRIPTION

FIG. 1 is a front perspective view of a first embodiment of a spray bottle, showing our new design; FIG. 2 is a front elevation view thereof; FIG. 3 is a right side elevation view thereof, with the left side elevation view being a mirror image of FIG. 3; FIG. 4 is a rear elevation view thereof; FIG. 5 is a bottom plan view thereof; FIG. 6 is a top plan view thereof; FIG. 7 is a front perspective view of a second embodiment of a spray bottle, showing our new design, wherein the crossed-line surface shading depicts a fabric material; FIG. 8 is a front elevation view thereof; FIG. 9 is a right side elevation view thereof, with the left side elevation view being a mirror image of FIG. 9; FIG. 10 is a rear elevation view thereof; FIG. 11 is a bottom plan view thereof; and, FIG. 12 is a top plan view thereof.

The broken lines immediately adjacent the shaded areas represent the bounds of the claimed design, while all other broken lines are directed to environment and are for illustrative purposes only; the broken lines form no part of the claimed design.
